ABSTRACT OF THE DISCLOSURE

A process for forming serrations on a face of a pipe flange involves the steps of forming a flange on the end of a pipe with a smooth surfaced forming means, replacing the flange forming means with a serrated forming means, and finish forming the flange with the serrated forming means to produce a flanged pipe having concentric serrations formed in the flange face.

This invention relates to a novel process for forming a flange on a pipe and for simultaneously forming serrations in a face of the formed flange. The process has special application to forming metal pipe products, however, it is useful for forming flanged pipes or tubes from other materials as well.

Method for forming flanges on the ends of pipes are generally well known in the art, as exemplified by the Lindberg Patent 1,421,507. Such prior art methods have utilized various forms of apparatus to lap or form an end portion of a pipe into an outwardly flared flange having a flat face which in use can be abutted against a similar flange on an adjoining pipe. In addition, separate methods have been used for forming grooves in the exposed flange face which is to be abutted against an adjoining flange, or other object, and serrated faces on such flanges offer certain advantages in retaining gasket material between adjoining pipe sections and in preventing cold flow of certain thermoplastic gasket materials. However, the formation of serrations on flange faces has been a costly operation since it requires one or more separate machining operations to complete the final pipe product. The Albro Patent 3,253,449 illustrates a pipe product having a typical end flange with concentric serrations, or grooves, formed therein. The Albro patent is also illustrative of the rather complex and costly assembly procedures which have been resorted to in providing serrated surfaces on pipe flanges. Also, other methods have been used which require a separate machining of concentric grooves in a pipe flange face after the flange has been formed in conventional forming apparatus.

The present invention is concerned with producing, in a single novel process, a flanged pipe product having serrations included in a face of the formed flange. According to the present invention, the serrations which are desired on a flange face are formed on the flange during the same process which develops the end of a pipe into a flanged structure. In one embodiment, the novel process partially develops a flange to something less than its full 90 degree position relative to the longitudinal axis of the pipe, and then the flange is finished to its final 90 degree position, or whatever angle may be desired, to include concentric serrations in the finished flange face. However, the process may alternatively develop serrations in the flanged end portion of a pipe during an earlier stage of the flange formation or simultaneously with the entire flange forming operation.

With the process of this invention, the desired pipe product is formed at a lower cost and with all of the

2

advantages of such a product as produced by prior costly methods requiring machining or similar operations after a flange has been formed on a pipe. Further, the process lends itself to the use of present day apparatus, with certain modifications which will be discussed in this application, and therefore, it is not necessary to replace present pipe forming apparatus with a new type of machinery.

Other advantages and features of the present invention will become apparent in the more detailed discussion which follows, and in that discussion reference will be made to the accompanying drawings in which:

FIGURE 1 represents an overall perspective view of apparatus used in a flange forming operation in accordance with the present invention;

FIGURE 2 illustrates in cross section a portion of a pipe end which is being held in a die shell to receive flanging and serrating operations in accordance with the invention, and an initial step in the process is illustrated;

FIGURE 3 illustrates a further step from that shown in FIGURE 2, and in this step the flange is partially formed to a position which is slightly less than its final relationship to the main body of the pipe;

FIGURE 4 is a similar view to FIGURES 2 and 3 and illustrates a final step in the process for finishing the flange and simultaneously applying serrations to a face of the flange, and

FIGURE 5 is an illustration of a roller device used with the apparatus of this invention to form serrations in the flange face of a pipe.

Flanges may be formed in end portions of pipes by working and bending the end portions radially outwardly against a die surface until a desired development of a flange has been attained. As already mentioned, the Lindberg patent illustrates suitable apparatus for developing a flange at a pipe end. The apparatus illustrated in the Lindberg patent is an example of an early arrangement for forming pipe flanges, but more recent apparatus has been used which places a roller means against an inner surface of a protruding pipe section for working the protruding section against a die shell in which the pipe is held. Such apparatus includes means for pneumatically or hydraulically positioning the roller device so that its axis of rotation may be changed relative to the longitudinal axis of the pipe. In this way, a roller means may be initially placed against the inside surface of a pipe end and rotated around the circumference of that surface to work that surface into a condition for shaping. The same roller means is then slowly adjusted in its position relative to the pipe so that the axis of rotation for the roller moves away from the central axis of the pipe, and thus the pipe end is ultimately developed into a flange which extends radially outwardly from the pipe and at approximate right angles to the central longitudinal axis of the pipe. Such apparatus is well known in the art forlapping or flanging pipe ends, but the prior methods have required additional apparatus and separate operations to finish formed flanges so as to include concentric serrations in their exposed face.

The general view in FIGURE 1 shows typical apparatus which may be used with the process of this invention for forming and serrating a flange on a pipe end. A die shell 10 is designed to carry a pipe section 12 which is to be formed with a flanged end, and the pipe section is placed in the die shell so as to leave an end portion 14 protruding therefrom. In the illustration of FIGURE 1, the end portion has been worked radially outwardly from the longitudinal axis A—A of the main pipe body so as to present the illustrated flange on the end of the main pipe body 12. FIGURE 1 also shows a roller means 16 positioned adjacent to the die shell for a working contact with the protruding end portion of the pipe. The roller means

16 includes a smooth working portion 18 which contacts the inner surface of the pipe end to develop it into the flange which is shown. Of course, the roller means 16 is suitably mounted on apparatus which can be moved toward and away from the die shell 10, and such conventional apparatus has been omitted from the drawings for clarity since machines of this type are well known in the art. The apparatus which carries the roller means 16 also includes means for moving the roller means about the circumference of the pipe end, and additionally, control means are included for changing the angle C between the central longitudinal axis A—A of the pipe and the axis of rotation B—B of the roller means. In a typical apparatus, the roller means is friction driven about its axis B—B while being orbited around the axis A—A of the pipe so as to contact and develop the protruding end portion of the pipe. As the flange is developed, a typical apparatus includes pneumatic means for changing the angle C between the axes A—A and B—B so that the roller means 16 causes the pipe end portion to bend outwardly against an outside surface of the die shell 10.

FIGURES 2 through 4 illustrate a series of steps in the process of the present invention, and the apparatus used is similar to that described for FIGURE 1. At the beginning of the process a pipe 12, or whatever other tubular structure is being worked, is placed within a bore of the die shell 10 so that an end portion 14 of the pipe protrudes out of the die shell, as illustrated. Then, the apparatus which carries the roller means 16 is moved toward the protruding end portion of the pipe to contact the inner surface of the end portion. The initial contact between the smooth surfaced roller 16 and the protruding end portion of the pipe is shown in FIGURE 2, and once the roller means is in position, the apparatus can be operated to orbit the roller about the entire circumference of the pipe end. As the roller means is orbited, the roller rotates on its axis B—B, and the smooth surface 18 of the roller begins to work the material of the protruding pipe portion.

Then the roller means 16 is slowly adjusted, such as by pneumatic control devices, to apply a pressure against the inner surface of the pipe end, and as the axis B—B is changed relative to a longitudinal axis of the pipe, the end portion is flared radially outwardly to form a flange. FIGURE 3 illustrates the partial formation of a flange, as developed from the end portion 14 of the main pipe body. In the FIGURE 3 position, the roller means 16 has been adjusted from the initial position shown in FIGURE 2 so as to develop a flange which approaches an approximate 90 degree angle relative to the longitudinal axis of the pipe. However, it has been found that the desired serrations for such a flange can be developed during the flange forming operation if the smooth surfaced roller is replaced by a serrated surfaced roller prior to the completion of the flange forming sequence.

FIGURE 4 shows that the roller with a smooth surface 18 has been replaced by the roller 20 having equally spaced annular grooves or serrations cut into its flange contacting surface. When the serrated roller 20 is engaged with the exposed flange surface (which was initially the inner surface of the pipe end 14), there are formed concentric serrations in the flange face corresponding to the grooves cut into the roller 20. After the roller 20 is engaged against the exposed flange face, it is then moved further by the abovementioned pneumatic means to press into the flange surface and to form the concentric serrations therein. In the preferred process, it has been found that the step of forming concentric serrations in the flange face should be applied before the flange is fully formed to its final position. In the usual flange formation, it is desired to produce a flange which extends radially outwardly from a pipe body at an angle of approximately 90 degrees as related to an axis of the pipe body. When such a flange is to be formed, it has been found that the initial steps of the process, which may include the use of a smooth

surfaced roller, should be applied until the flange is partially formed to a position within the range of 86 degrees to 88 degrees as related to the central longitudinal axis of a uniform diameter pipe. When this partially formed flange has been produced, the pipe is removed from holding dies, and the smooth surfaced roller is replaced by a serrated surfaced roller, which is more completely illustrated in FIGURE 5. Then the pipe is reinserted in the holding dies, or die shell, and the final forming and serrating takes place while the flange is being developed to its final position of approximately 90 degrees as related to the pipe body. FIGURE 4 illustrates the final position of the serrated roller for forming such a 90 degree flange, and also a specially shaped die shell is illustrated wherein the upright face portion 24 of the die shell is shaped to receive the back side of the formed flange. The usual die shell face is flat as indicated by the dotted lines X—X, and the die shell which is used with this invention is built up to support the flange during the serrating operation. Also the corner 26 of the die is shaped with a radius to accommodate the formed radius on the back side of the flange.

As an example of the present invention, a serrated roller has been used which produces spaced serrations having flat topped peaks of approximately .020 inch in width and having groove walls between the peaks that are at 45 degree angles to the flat peaks. Various diameter rollers may be used in accordance with the size of pipe flange which is to be formed, and pipe sizes ranging from $\frac{1}{2}$ inch to 6 inches (with outside diameters from .840 to 6.625 inches) have been formed with serrated flanges having outside diameters for the laps ranging from $1\frac{1}{8}$ inches to $8\frac{1}{2}$ inches. The serrations formed in the various pipe sizes are of the desired configuration and offer all of the advantages and features of machined serrations formed by separate processes. The process of this invention is useful for forming pipes made from various metal materials, such as copper, aluminum, brass, carbon steel, Monel, nickel, Inconel and stainless steel, and also for non-metal materials.

Although the process has been primarily described as including an initial use of a smooth surfaced roller, it is also possible to form the serrated flange by using a serrated roller for the entire flanging operation. The use of one method or the other will depend upon the type of material which is being worked, and further, it may be necessary to include an annealing step prior to the final formation of a metal serrated flange which uses both types of rollers to obtain the final flange product. Also, the apparatus which is used to carry out the invention may utilize more than one roller at a time and many variations in apparatus are possible to carry out the steps of the novel process. The process is especially useful for serrating pipe flanges simultaneously with the roll forming of such flanges, but it is also contemplated that the roll serrating part of the process can be applied to preformed flanged pipes. Other modifications and changes in the process will become apparent to those skilled in the art and such changes are intended to be included within the scope of this invention.

What is claimed is:

1. A process for forming pipe with a flange having concentric serrations included on a face of the flange comprising the steps of:

placing a pipe, or other tubular stock, within a bore of a die shell with an end portion of said pipe protruding from said die shell,

contacting an inner surface of said protruding pipe portion with a smooth surfaced roller,

moving said smooth surfaced roller relative to said pipe so as to contact all of the inner pipe surface about its entire circumference while maintaining a flat smooth surface of said roller in contact with the inner pipe surface,

forming a flange on said pipe by bending said protruding pipe portion outwardly away from a central longitudinal axis of said pipe, said forming step being accomplished by changing the relative angle between the surface of said roller and the central longitudinal axis of said pipe so as to form the protruding end portion of the pipe into a flange, removing said smooth surfaced roller from contact with the protruding portion of the pipe when a flange is partially formed and replacing the smooth surfaced roller with a roller having serrations formed about its surface, engaging said serrated roller surface with the partially formed flange, and pressing the serrated roller surface against the exposed flange face to finish forming a flange and to simultaneously form concentric serrations in the face of said flange.

2. The process of claim 1 wherein said rollers rotate about central longitudinal axes while contacting their respective surfaces with the inner surface of said protruding pipe portion.

3. The process of claim 1 wherein said rollers are moved about the circumference of said protruding pipe portion while the pipe is held stationary in said die shell.

4. The process of claim 1 wherein said pipe is rotated when said rollers are in contact with the inner surface of the protruding pipe portion.

5. The process of claim 1 wherein said flange is partially formed by said smooth surfaced roller to an angle of less than 90 degrees relative to the longitudinal axis of said pipe, and then finish formed with said serrated roller to an angle of substantially 90 degrees.

6. The process of claim 5 wherein said flange is partially formed by said smooth surfaced roller to an angle of approximately 86 degrees.

7. A process for forming serrations on a face of a pipe flange simultaneously with the formation of the flange itself, comprising the steps of:

contacting an inner surface of an end portion of a pipe with a smooth surfaced flange forming means, moving the smooth surfaced flange forming means and pipe relative to one another to bend the end portion of the pipe outwardly into a flange shape, replacing the smooth surfaced flange forming means with a serrated forming means, and finish forming the flange with said serrated forming means to produce a flanged pipe having concentric serrations formed in the flange face.

8. The process of claim 7 wherein said serrated forming means replaces the smooth flange forming means before the flange has been fully turned to a 90 degree angle relative to a longitudinal axis of said pipe.

9. The process of claim 8 wherein the replacement step is made when the flange is partially formed at an angle of approximately 86 degrees relative to a longitudinal axis of the pipe.
